UNITED STATES PATENT OFFICE.

EDWARD SADLER, OF UPPER TOOTING, ENGLAND.

ELECTRIC INDICATOR.

SPECIFICATION forming part of Letters Patent No. 760,568, dated May 24, 1904.

Application filed May 16, 1903. Serial No. 157,432. (No model.)

To all whom it may concern:

Be it known that I, EDWARD SADLER, a subject of the King of England, residing at Upper Tooting, England, have invented certain new and useful Improvements in Electric Indicators, of which the following is a specification.

The present invention relates to improvements in electric indicators for bells or other purposes; and the principal object is to automatically reset the previous disk or other indicating device operated on a subsequent call or signal being given, such last indication being visible until a further signal is given from another point or in some cases for a longer time.

In the accompanying drawings, Figure 1 is a side view of one form of the improved indicator for use with electric bells. Fig. 2 is a sectional plan on line 2 2 of Fig. 1. Figs. 3 and 4 are front views of the indicator-disk and shield therefor, respectively. Fig. 5 is a front view of a modified form of indicator. Fig. 6 is a side view thereof. Fig. 7 is a sectional plan on line 7 7 of Fig. 6, and Fig. 8 is a diagram showing the method of connecting up the indicators.

The apparatus comprises for each disk or other indicating device a metal frame *a* or casing having suitable means of attachment to an indicator or base-board—for instance, two lugs *a'*, cut out and bent up from the metal—and in said casing are mounted two coils *A* and *C*, one of which, *A*, is hereinafter termed the "adjusting" or "resetting" coil and the other, *C*, the "indicating-coil." One of these coils—for example, in Figs. 1 and 2 the resetting-coil *A*—is wound round a soft-iron core *B*, having its ends projecting beyond the coil and bearing in the casing, as at *b*. The other coil, *C*, is then wound on a bobbin *c*, loosely surrounding the soft-iron core *D*, pivoted at its ends in the casing by means of pivots *d*, and to the ends of said core *D*, and preferably at right angles thereto, are attached two soft-iron arms or pole-pieces *E*, projecting in the same direction. To said arms or to the core *D* is attached a light sheet of metal or other suitable material forming the indicating-disk *F*, which is by preference bent to form an arc of a cylinder. The loose core *D*, arms *E*, and in-

dicating-disk *F* are adapted to rock easily on the axis or pivots of said loose core, stops being provided to limit the movement.

Upon one side—for instance, the convex side—of the indicating-disk *F*, are alternately marked light and dark or suitable different-colored lines or other devices *f'* and *f''*, those of one color being slightly wider than those of the other color, and close to and in front of said disk, but without touching it, is a plate *G*, preferably bent similarly to the disk and having apertures *g'* approximately corresponding in number, width, and distance apart to the one-colored lines or devices on said disk. This slotted plate may be fixed to the casing *a* or to any other fixed part of the apparatus, as desired.

The arms or pole-pieces *E*, and consequently the disk *F*, connected thereto, are prevented from rotating too far in one direction by coming in contact with the ends of the core *B* of the resetting-coil *A* and in the other direction by a suitable stop or stops *e*.

The core *D*, to which the arms *E* are attached, may be so adjusted or balanced that the disk *F* may be stationary when the arms are either in contact with the ends of the adjusting-coil core or with the stop or stops *e*.

The different indicators may be suitably connected up, for instance, as follows, reference being had to Fig. 8: Each indicating-coil *C*, *C'*, or *C''* has one end of its wire in connection with its respective "push" or other contact device *x*, *x'*, or *x''* by wires 1 2 3, respectively, all the other ends being carried to a general binding-screw *I* by wires 3' 4 5, with which also is connected one end of the wire 6 of the adjusting-coil *A* of the first indicator, the other end of which is connected by wire 7 with the coil *A'* of the second indicator and that by wire 8 with the third, *A''*, and so on—that is, the adjusting-coils *A*, *A'*, and *A''* are all connected in series. When contact is made—say at *x*—the current travels through wire 9 from the battery *z* through the push and wire 1 round the indicating-coil *C*, then over wire 3 to the general binding-screw *I*, and from the latter over wire 6 round the adjusting-coil *A* of the first indicator, then in series over wires 7 and 8 round the similar coils *A'* and *A''* of the other

indicators, and finally back by wire 10 and bell y to the battery. The coils are so connected and their wires so wound that similar poles will be induced at similar ends of the 5 cores of any one indicator. It will be seen that in the indicator representing the first push both coils A and C will have the current passing round them, which being in a similar direction both cores will consequently become 10 similarly magnetized, and as the arms or pole-pieces E aforesaid are attached to the core D of the indicating-coil C they will be repelled by the core B of the adjusting-coil A and the indicator-disk F, attached to said arms, moved 15 so that the light colored lines, for instance, will show opposite the slots in the outer plate G and indicate that this disk has been operated. Should a signal be given—that is, contact made—from another point—say at x' —the 20 current will flow as in the first case, but with the difference that instead of passing through the indicating-coil C of the first indicator it will now pass to the corresponding coil C' of the second indicator. The pole-pieces E' of 25 this indicator will be repelled and indication made; but with regard to the first indicator as the current is only passing through the adjusting-coil A thereof its core B is magnetized and will consequently attract the arms E, so that this indicator is reset to its normal 30 non-indicating position.

Referring to Figs. 5, 6, and 7, in conjunction with the above indicator I may when desired use a vibrating disk H, preferably two-colored and moving behind a slotted plate J and so arranged as to be operated by the attraction of an armature H' (attached thereto and suspended from the casing at H²) by the core of the indicating-coil C' at the same time 35 as the arms E of the coil A'' are repelled to operate the main indicator-disk F, as above stated. As the indicating movement of the indicator-disk depends upon the mutual repulsion of the similar poles of the cores B and 40 D and the resetting movement on the attraction of either for the other, it is immaterial which of the coils in Figs. 1 and 2 be used as indicating-coil and which as resetting-coil. It is therefore equally immaterial whether 45 the oscillatory core D, carrying the pole-piece, be within coil A or coil C. In Figs. 5 to 7 it is shown in the coil A'', because the coil C'' nearer the armature H' must in this case be used as indicating-coil. The arrangement 50 of disk H is for the purpose of allowing the indication to remain visible for a longer time after the main indicator-disk F has been reset should two signals be given or contact made in quick succession from two different points, 55 since disk H acts as a free pendulum and continues to oscillate for some time when once set in motion.

A collar b³ or a stop or stops b⁴ c³, Figs. 1 and 5, of diamagnetic material, may be placed 60 on the cores of the indicating and resetting

coils to prevent too strong an attraction of the arms E or armature H', respectively.

I do not confine myself to the arrangements, constructions, and connections above set out, as the same may be varied within wide limits 70 without departing from the spirit of the invention.

The invention with suitable modifications may also be adapted to other indicating means than for electric bells, as described—for instance, to ship's engine-room and conning-tower indicators or telegraphs, railway-station and signal-box indicators or instruments, and so on.

I declare that what I claim is—

1. In a signal-indicating system the combination of a series of indicating-coils severally connected electrically to the points whence signals are to be transmissible a corresponding series of resetting-coils collectively connected in series and common to all the signal-circuits, said indicating and resetting coils being located in pairs with their similar poles adjacent to one another, a series of vibratory pole-pieces located to be magnetized by one 90 of said coils to be respectively repelled from the other coil when current is flowing in both coils of a pair and to be attracted when one of said coils is idle and a series of corresponding signal-disks movable with said pole-pieces. 95

2. In a signal-indicating system the combination of a series of indicating-coils, severally connected electrically to the points whence signals are to be transmissible, a corresponding series of resetting-coils collectively connected in series and common to all the signal-circuits, said indicating and resetting coils being located in pairs with their similar poles adjacent to one another, soft-iron cores in 100 said coils, vibratory pole-pieces on one of said cores of each pair, movable to and from the other core of the pair and a series of corresponding signal-disks connected to said pole-pieces. 105

3. In a signal-indicating system the combination of a series of indicating-coils severally connected electrically to the points whence signals are to be transmissible, a corresponding series of resetting-coils, collectively connected in series and common to all the signal-circuits, said indicating and resetting coils being located in pairs with their similar poles adjacent to one another, soft-iron cores in 110 said coils, vibratory pole-pieces on one of said cores of each pair, movable to and from the other core of the pair and a series of corresponding signal-disks connected to said pole-pieces. 115

4. In an electric signal-indicator the combination of a frame, a core of soft iron fixed in said frame, a coil surrounding said core, a core of soft iron parallel to the aforesaid core 120

journalized in said frame, a coil surrounding said journalized core, two pole-pieces extending from the ends of the journalized core and extended to contact with the fixed core, a stop 5 for limiting the movement of said pole-pieces away from the fixed core, an indicating-disk attached to the journalized core and means for passing electric current through both said cores in the same direction or alternatively

through one of them, only, for the purpose to set forth.

In witness whereof I have signed this specification in the presence of two witnesses.

EDWARD SADLER.
